[57] **CLAIM**

The ornamental design for an invertible table and rocker combination, as shown.

DESCRIPTION

FIG. 1 is a perspective view of an invertible table and rocker combination embodying my new design; FIG. 2 is a side elevational view taken from the right in FIG. 1;

FIG. 3 is an end elevational view taken from the left in FIG. 1; and

FIG. 4 is a perspective view of the invertible table and rocker combination showing same in its inverted position for use as a rocker.

FIG. 1

FIG. 2

FIG. 3

FIG. 4
